UNITED STATES PATENT OFFICE.

CHARLES L. GOODRUM, OF NEW YORK, N. Y., ASSIGNOR TO WESTERN ELECTRIC COMPANY, INCORPORATED, OF NEW YORK, N. Y., A CORPORATION OF NEW YORK.

CALLING DEVICE.

1,369,022.

Specification of Letters Patent. Patented Feb. 22, 1921.

Application filed September 14, 1917. Serial No. 191,365.

To all whom it may concern:

Be it known that I, CHARLES L. GOODRUM, a citizen of the United States, residing at New York, in the county of New York and 5 State of New York, have invented certain new and useful Improvements in Calling Devices, of which the following is a full, clear, concise, and exact description.

This invention relates to calling devices 10 of the type employed in directly controlled machine switching telephone systems and has for its object the provision of an improved form of calling device.

A feature of this invention is the provision 15 of means for varying the character of the trains of impulses transmitted to a telephone line by the operation of a calling dial of the ordinary type.

According to the above mentioned feature, either one of two trains of impulses 20 may be transmitted in response to each actuation of the dial. The train of impulses transmitted depends upon the position of a key which in one position shunts a certain 25 number of impulses, and which when in another position, opens this shunt to allow these impulses to be transmitted over the telephone line in addition to the number dialed. The result of this arrangement is 30 that more than ten impulses may be sent in a train of impulses by an ordinary ten position dial.

In the preferred embodiment of the invention, as shown on the accompanying 35 drawing in which the figure is a diagrammatic representation of a calling device and the circuit connection therefor, one key controlling ten impulses is shown. The calling device may be of the well known type such 40 as is disclosed in Patent 1,161,854, issued November 30, 1915 to O. F. Forsberg, with the exception that there are two impulse 45 wheels 1 and 2 mounted upon the shaft 3, instead of only one impulse wheel as shown in the above mentioned patent.

Coöoperating with the wheel 1, there is a roller 10 which is fastened to a contact spring 4 in such a manner that when the wheel 1 is rotated in a clockwise direction, 50 the roller 10 will ride over the teeth of wheel 1 without breaking the contact between springs 4 and 5, but when the wheel is rotated in the opposite direction each tooth of the wheel 1 will cause the springs 4 and 5 to open. A roller 6 is in engagement with the

wheel 2 in a similar manner and controls the contact springs 7 and 8.

Each wheel is provided with ten teeth spaced about half its circumference, but these wheels are so mounted on the shaft 3 60 that when the shaft is moved from normal in a clockwise direction, all the teeth of wheel 2 will engage roller 6 before the first tooth of wheel 1 engages the roller 10. A dial 11 is fastened to the shaft 3 and is actuated by 65 means of finger holds 12 provided around half its periphery. These holds are arranged to correspond with the teeth on the wheel 1.

The contact springs 4, 5, 7 and 8 are connected in series with one side of a telephone line. Normally the springs 7 and 8 are shunted by means of springs 14 and 15. A key is attached to the impulse sender in any 70 well-known manner and is arranged to open the contacts 14 and 15 when depressed. The key is held in its depressed position by a catch 17 until released by the dial reaching its normal position after being actuated, at which time a lug 18 on the circumference of 75 80 the dial 11 engages a pivoted lever 19 which in turn engages the catch 17 and releases the key 16 which is returned to its normal position by a spring (not shown).

Let us suppose that three impulses are to 85 be sent. In this case the key 16 is not operated so that the user merely engages with his finger the finger hold 12 opposite the number 3 and rotates the dial in a clockwise direction until a stationary stop 20 is reached. 90 In response to the actuation of the dial 11 the shaft 3 and the impulse wheels 1 and 2 are rotated in a clockwise direction. The rotation of the dial also causes the winding up of a motor spring 13 in a well-known 95 manner.

During the forward rotation of the impulse wheels 1 and 2 the rollers 10 and 6 are moved away from the contact springs 4 and 7 when engaged by the teeth of the impulse 100 wheels 1 and 2 respectively and therefore do not cause the opening and closing of the contact springs 4 and 5 and 7 and 8.

When the user's finger engages the stop 105 20, the positions of the wheels are such that the roller 10 is between the third and fourth teeth of the wheel 1. When the user releases the dial 11, *i. e.*, removes his finger from the engaged finger hold, shaft 3 and the elements fastened thereto are rotated in 110

a counter-clockwise direction by the spring 13. Impulse wheel 1 now vibrates the roller 10 so as to open and close the contact springs 4 and 5 three times. As soon as the first 5 tooth of wheel 1 leaves the roller 10, the last tooth of wheel 2 engages the roller 6. During the remainder of the backward movement of the shaft 3, the roller 6 is vibrated so as to open the contact springs 7 and 8 10 ten times, but due to the short circuit about these springs through springs 14 and 15, these ten impulses are not sent out over the telephone line.

It will now be obvious that if thirteen impulses are desired, all that is necessary is to 15 press the key 16 and operate the dial just as if three impulses were to be sent out. In this case since springs 7 and 8 are not short-circuited, just as soon as the wheel 1 has 20 finished sending out three impulses, the wheel 2 will commence to send out ten impulses, making thirteen in all. By this arrangement any train of impulses from one to ten can be sent with an ordinary ten position dial when the key is not depressed; 25 any train of impulses from eleven to twenty can be sent if the key is depressed.

What is claimed is:

1. In a calling device, a dial, means responsive to the actuation of said dial for producing different series of like impulses, a key, and means responsive to the actuation of said key for increasing the number of impulses in each of said series.
2. In a calling device, two impulse wheels, one of said wheels arranged to produce different series of impulses, and a key for nullifying the impulses produced by one of said wheels.
3. In a calling device, a dial, two impulse wheels, one of said wheels being arranged to produce a definite number of impulses upon the actuation of said dial, the other wheel being arranged to produce a number of impulses depending upon the displacement of

the dial, and a key arranged for determining whether the impulses produced by the first mentioned wheel shall be effective.

4. In a calling device, a dial, two impulse wheels actuated in response to the operation 50 of said dial, one of said wheels being arranged to produce a train of impulses before the other starts to produce impulses, and a key for determining whether the impulses produced by the last mentioned wheel shall 55 be effective.

5. In a calling device, a dial, means for producing a series of impulses by the actuation of said dial, and a key for determining whether certain of the impulses shall be effective. 60

6. In a calling device, a rotatable shaft, a dial and two impulse wheels secured thereto, said impulse wheels being arranged to produce a continuous series of impulses, and a 65 key for determining whether those impulses produced by one of said wheels shall be effective.

7. In a calling device, a rotatable shaft carrying two impulse wheels, a dial secured 70 to said shaft for actuating said impulse wheels, means including one of said wheels for producing different series of impulses in response to the angular displacement of said dial, means including the other of said 75 wheels for producing and adding to said series of impulses another series of a definite number to form a continuous longer series, and means including a key for nullifying the impulses produced by the last said wheel. 80

8. In a calling device, two impulse wheels, one of said wheels arranged to produce different series of impulses, and a key for determining whether the impulses of the other wheel should be effective. 85

In witness whereof, I hereunto subscribe my name this 8th day of September, A. D. 1917.

CHARLES L. GOODRUM.
